UNITED STATES PATENT OFFICE.

JOHN H. KELLOGG, OF BATTLE CREEK, MICHIGAN, ASSIGNOR TO SANITARIUM AND HOSPITAL EQUIPMENT COMPANY, OF BATTLE CREEK, MICHIGAN.

CHAIR.

Application filed July 21, 1924. Serial No. 727,282.

To all whom it may concern:

Be it known that I, JOHN H. KELLOGG, a citizen of the United States, residing at Battle Creek, county of Calhoun, State of Michigan, have invented certain new and useful Improvements in Chairs, of which the following is a specification.

This invention relates to improvements in chairs.

10 The main object of this invention is to provide an improved chair adapted to support the body of the occupant in a natural and helpful position and also one which tends to cause the occupant to assume that 15 position when occupying the chair.

A further object is to provide a chair having these advantages which is attractive in appearance.

Objects relating to details and economies 20 of construction and operation will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated in the accompanying drawing, forming a 30 part of this application, in which:

Fig. I is a perspective view of a chair embodying the features of my invention.

Fig. II is a fragmentary vertical central section on a line corresponding to line 2—2 35 of Fig. III.

Fig. III is a horizontal section on a line corresponding to line 3—3 of Figs. I and II.

In the drawing similar reference characters refer to similar parts throughout the 40 several views, and the sectional views are taken looking in the direction of the little arrows at the ends of the section lines.

Referring to the drawing, the seat 1 of the structure illustrated is an upholstered 45 seat which is suitably mounted upon the frame 2, the front legs 3 being secured in the usual or any desired manner, the joints of the frame and legs not being illustrated.

The rear legs 4 are extended upwardly 50 into back side posts 5. These posts are connected at their upper ends by the top cross bar 6, this bar being straight. The bottom cross bar 7 extends between the posts, the bar 7 having a rearwardly bowed central

portion 8, this bowing or curving being 55 quite substantial in degree.

I provide vertical slats 9, 10 and 11, the slat 9 being the center slat, the slats 11 the outer slats, and the slats 10 intermediate slats. These slats are bowed forwardly with 60 an irregular curvature so that the crown of the bows on the most forward portion thereof is below the longitudinal center of the slats. The degree of curvature or bowing of the slats increases from the center 65 slat 9 to the outer slats, that is, the degree of the bowing of the slats 10 exceeds that of the center slats and the bowing of the outer slats 11 exceeds that of the slats 10. This results in a back having a horizontally concaved lower portion which merges upwardly into a horizontally concaved vertically convex intermediate portion which in turn merges upwardly into a substantially flat rearwardly inclined upper 70 75 portion.

In a chair thus formed, the body of the occupant is supported from the hips to the shoulders, the rearwardly curved or convex portion at the back accommodating the hips 80 of the person when seated well back in the chair, the intermediate portion supporting the small of the back and the upper flat portions supporting the shoulders. The back has a general rearwardly inclination 85 so that the shoulders may be thrown well back, bringing the head to a proper poise so that the body is perfectly balanced and the occupant seats easily and comfortably 90 in the chair.

My improved chair supports the body in a helpful position and also has the advantage of tending to cause the occupant to assume that position.

I have illustrated my improvements as I 95 have embodied the same in a dining chair. I have not attempted to illustrate or describe the adaptation thereof to rocking or other chairs as I believe the disclosure made will enable those skilled in the art to embody or adapt the same as may be desired. 100

Having thus described my invention, what I claim as new and desire to secure by Letters Patent, is:

1. In a chair, the combination with a 105 rearwardly inclined seat, of a back comprising rearwardly inclined posts, a straight top cross bar connecting the upper ends of said

- posts, a bottom cross bar disposed in spaced relation to said seat and having a rearwardly bowed central portion of substantial curvature, and a plurality of vertically disposed slats extending between said cross bars, said slats being forwardly bowed with an irregular curvature, the bowing of the slats increasing from the central slat toward each side of the back, whereby a back is provided having a horizontally concaved lower portion merging upwardly into a horizontally concaved and vertically convex intermediate portion which merges upwardly into a substantially flat upper portion.
- 5 10 15 20 25 30 35 40 45 50
2. In a chair, the combination with a seat, of a back comprising posts, a top cross bar connecting the upper ends of said posts, a bottom cross bar disposed in spaced relation to said seat and having a rearwardly bowed central portion of substantial curvature, and a plurality of vertically disposed slats extending between said cross bars, said slats being forwardly bowed with an irregular

lar curvature, the bowing of the slats increasing from the central slat toward each side of the back, whereby a back is provided having a horizontally concaved lower portion merging upwardly into a horizontally concaved and vertically convex intermediate portion which merges upwardly into a substantially flat upper portion.

3. In a chair, the combination with a seat, of a back comprising posts, a top cross bar, a rearwardly bowed bottom cross bar, and a plurality of vertically disposed forwardly bowed slats extending between said cross bars, the bowing of the slats increasing from the central slat toward each side of the back, whereby a back is provided having a horizontally concaved lower portion merging upwardly into a horizontally concaved and vertically convex intermediate portion which in turn merges upwardly into a substantially flat upper portion.

In witness whereof I have hereunto set my hand.

JOHN H. KELLOGG.
